UNITED STATES PATENT OFFICE.

CHARLES MOORE, OF CHICAGO, ILLINOIS, ASSIGNOR TO C. A. TAYLOR TRUNK WORKS,
OF CHICAGO, ILLINOIS, A CORPORATION OF ILLINOIS.

REENFORCING MEANS.

Application filed November 12, 1921. Serial No. 514,437.

To all whom it may concern:

Be it known that I, CHARLES MOORE, a citizen of the United States, residing at Chicago, in the county of Cook and State of Illinois, have invented certain new and useful Improvements in Reenforcing Means, of which the following is a specification.

The present invention relates to reenforcing means.

10 The present invention has been illustrated in connection with a drawer of a wardrobe trunk. It is common practice to reinforce the edges of such drawers with strips of metal fastened to adjacent sides, thereof, 15 whereby to reduce the danger of the sides of the drawer pulling apart in service.

An object of the present invention is to provide reenforcing means for drawers, boxes or similar articles which presents a 20 good appearance and which will effectually prevent the pulling apart of the sides of said drawer or other article.

A further object is to provide a reenforcing means which will present a good appearance on the front side of the drawer and which will present no outstanding edges on 25 said front side.

Further objects will appear as the description proceeds.

30 Referring to the drawings,

Figure 1 represents a drawer or box employing one embodiment of the present invention.

Figure 2 is a sectional view taken along 35 the line 2-2 of Figure 1.

Figure 3 is a view in section illustrating the manner of applying the improved reenforcing means.

Figure 4 is a view of a strip of metal before being applied to a drawer or box for 40 reinforcing purposes.

The numeral 10 indicates a drawer or box having the front member 11 and the side members 12-12. The bottom member of 45 said drawer or box is indicated by the numeral 13. The various members which go to make up the box 10 will be suitably joined together, as for instance, by means of cement and nails, the joints between certain of the 50 members being reinforced by metal strips to prevent said members from pulling apart. The front member 11 is connected to each of the end members 12-12 by means of a reenforcing strip which is indicated by the numeral 14. Said reenforcing member 14 may

be made from a blank such as illustrated in Figure 4, which may be considered as being divided into three longitudinal sections 15, 16 and 17 indicated by the broken lines 15', and 16'. The section 16 has a tongue 18 which projects beyond the boundaries of strips 15 and 17.

In applying the metal strip 14 to the box or drawer 10, the section 15 is applied to the edge of the member 11 with that side of the section 15 which faces the observer in Figure 4 placed against the member 11. The section 15 is attached to the member 11 by means of tacks indicated by the numeral 18 in Figure 1. The strip 14 may then be bent along the line indicated by the dotted line 15' to a position parallel and in contact with the section 15. The strip 14 is then bent again along the line indicated by the dotted line 16' which line will coincide with the edge between the front member 11 and side member 12. The section 17 will be moved into contact with the end member 12 and will be fastened thereto by means of the tacks 20-20. The tongue 19 will be bent around the lower edge of the front member 11 and will be held in contact with the bottom of the drawer or box by means of the tack 21. The end member 12 will preferably have reenforcing connection with the bottom member 13 by means of the reenforcing strip 22-22 which is bent along the line marking the edge of side member 12 and bottom member 13. Said reenforcing member 22 will be attached by means of tacks and will overlap 85 the lower end of strip 17 and tongue 19 of the reenforcing strip 14. It will be clear, of course, that the section 16, instead of lying flat against section 15 may be given other conformations whereby to present an 90 improved appearance.

The present invention has the advantage that the tacks holding the reenforcing member 14 to the front side of the drawer or box will be invisible and has the further advantage that no outstanding sharp edges will appear on the front of the said drawer or box. The turned over tongue 19 will securely hold the strip 14 in place at the bottom edge of the front member 14 and the double ply of material presented at the front of the drawer or box provides a very strong and durable reinforcement.

One embodiment of the present invention has been described in detail. Many modifi- 110

cations will occur to those skilled in the art. It is intended in this patent to cover all such modifications that fall within the scope of the invention as defined by the appended 5 claims.

I claim:

1. In combination, a drawer, integral re-enforcing means for said drawer, said re-enforcing means comprising a portion lying flat against one side of said drawer, a bent over portion lying parallel with and in contact with said first mentioned portion, a second bent over portion lying in contact with an adjacent side of said drawer, one of said 10 bent over portions having a tongue bent over into contact with a third side of said drawer.
2. In combination, a drawer, integral re-enforcing means for said drawer, said re-enforcing means comprising a piece of metal having one portion attached to one side of 15 said drawer adjacent to the edge thereof, attaching means extending through said portion, a second portion folded over said first portion to hide said first portion and said portion to hide said first portion and said

attaching means, and a third portion forming a continuation of said second portion folded over at right angles to said first portion and attached to an adjacent side of said drawer. 25

3. In combination, a drawer, integral re-enforcing means for said drawer, said re-enforcing means comprising a piece of metal having one portion attached to one side of said drawer adjacent to the edge thereof, attaching means extending through said portion, a second portion folded over said first portion to hide said first portion and said 30 attaching means, and a third portion folded over at right angles to said first portion and attached to an adjacent side of said drawer, 35 one of said portions having a tongue extending beyond the extremities of said other portions, said tongue being folded at right angles to said one portion for attachment to a third side of said drawer. 40

Signed at Chicago, Illinois, this 9th day 45
of November, 1921.

CHARLES MOORE.
